Application July 7, 1938, Serial No. 218,022

22 Claims. (Cl. 62—17)

This invention relates to improvements in air refrigerating and circulating facilities for railway refrigerator cars; and more particularly to improvements in so-called overhead ice bunkers for the merchandise chambers of railway refrigerator cars and to improved means for circulating refrigerated air within a railway refrigerator car. The present invention, however, is also applicable to cars, trucks, ships and storage houses, generally, which require refrigeration to preserve the merchandise being transported or stored.

The conventional railway refrigerator cars now in general use are equipped with ice bunkers located at each end of the car. This type of ice bunker construction has certain definite disadvantages.

The conventional end ice bunkers of a railway car usually have a combined ice capacity of about five tons. Nevertheless, the total area of exposed surfaces presented by such an amount of ice for cooling the circulating air by direct contact therewith is comparatively small. This area might be increased to some extent by use of so-called divided basket bunkers for the car end ice bunkers, but would still be less than that desired. The greatest possible surface contact between the ice and the air is desired as it facilitates cooling of the air and thereby promotes rapid movement of the air in its circulation between the car lading space and the ice bunkers.

In railway cars having conventional end ice bunkers, the circulating air must travel between the center or the door-way section of the car lading space and the opposite ends thereof to provide for both cooling of the air and refrigerating of the entire shipment of merchandise. The circulating air, therefore, has a relatively great distance to travel in a complete cycle for refrigerating the car lading space. This substantial distance of travel for the refrigerating air reduces its rate of circulation. The rate of circulation of air in a refrigerator car is dependent not only on the difference between the temperature of the transported perishable commodities and the temperature of the melting ice and on the rapidity with which the ice cools a given quantity of air, but also on the distance the circulating air must travel in a complete cycle of movement.

The use of overhead ice bunkers in railway refrigerator cars has been, heretofore, proposed to overcome some of the disadvantages of end ice bunker constructions. It is recognized that the upper portion of the car is the most advantageous location for ice bunkers and that an arrange-

ment of overhead ice bunkers along the entire length of the car may result in more rapid refrigeration and in a more uniform temperature throughout the car lading space. Nevertheless, 5 overhead ice bunkers have not, heretofore, come into general use for railway refrigerator cars. The previously proposed installations of overhead ice bunkers have certain objectionable features which preclude their acceptance in the railway art. One of the disadvantages in the prior proposals for overhead ice bunker installations is that they require very large supplies of ice and excessively heavy supports. Such installations would result in a top-heavy and, therefore, 10 impractical car. The prior art overhead ice bunkers present still another objection. Such ice bunkers extended across the entire width of the car lading space, and made it difficult to prevent water or condensation from dripping on the lading.

The present invention provides a structure, which not only eliminates the disadvantages of the above described prior railway car end and overhead ice bunkers, but which also presents a 15 number of important improvements in the general facilities for refrigerating railway cars.

The present invention in the preferred embodiment illustrated by the accompanying drawings includes overhead ice bunkers or ice tank units. 20 These novel overhead ice bunkers offer all the advantages of the prior art overhead ice bunkers, as well as a number of additional advantages.

The overhead ice bunker installations of this 25 invention are distinctly effective and efficient for car refrigeration. With railway car installations of the present invention, the extent of travel of circulating air in a complete cycle is limited by the width of the car lading space rather than controlled by the length of the car lading space as is the case where end ice bunkers are provided. 30 This invention, therefore, provides for more rapid cooling of the merchandise to be refrigerated. Furthermore, the ice bunkers of this invention provide for the ice being spread out or distributed 35 over such a relatively large area that the refrigerating action of the ice upon the air to be cooled will be greatly facilitated and promote rapid circulation of the air. Another advantage afforded 40 by the overhead ice bunkers of this invention is that they present a relatively large bottom surface for heat exchange contact with air to be cooled.

It is, therefore, an object of the invention to 45 provide overhead ice bunkers or tank units of

such construction that the overhead weight of the car, when provided with such tank units filled with ice, will be within permissible and practical limits and will be equalized between the car ends.

A further object of this invention is to provide overhead ice tank units at diagonally opposite corners of a refrigerator car and thereby leave the center or doorway section of the lading space unobstructed from car floor to car ceiling.

Another object of this invention is to provide overhead ice tank units at diagonally opposite corners of the car roof and to so support the ice tank units that the car lading spaces adjacent thereto will be free of obstructions from car floor to car ceiling.

Another object of this invention is to provide overhead ice bunkers or tank units of such construction as to require only a relatively small depth and to allow additional headroom below the overhead ice tank units.

Another object of this invention is to provide railway cars with overhead ice bunkers which are formed in sections or units that may be installed or removed independently of one another.

A still further object of this invention is to provide overhead ice tank units for holding an ice and salt mixture and also retaining a brine concentrate, whereby the tank units will combine the advantages of cooling by direct contact with ice and cooling by direct contact with refrigerated tank surfaces.

Another object of this invention is to provide railway cars with overhead ice tank units of such construction that the car is adapted for use in either refrigerating or ventilating its shipment of merchandise. If desired, the car may also be provided with heating service by placing car heaters in the doorway section of the car lading space or below the car floor.

Another object of this invention is to provide an overhead type of ice tank unit, in which the bottom thereof is of such construction as to provide a support for the ice and also channels below the ice for draining the water and/or brine resulting from ice meltage.

Another object of this invention is to provide an overhead ice tank unit with such construction for its exterior walls that they will not only contribute to the rigidity of the unit but will also present an extensive area of surface for exposure to circulating air and effect a more rapid circulation of the air over, through and around said ice tank unit.

Another object of this invention is to provide an ice tank unit with partition members extending between its inner side walls to reinforce the ice tank unit, to prevent splashing of liquid within the unit, and to prevent shifting of the ice within the unit.

A still further object is to provide improved supporting means for overhead ice bunkers.

A further object is to provide improved means for distributing refrigerated air into a car lading space, whereby a more uniform temperature is secured throughout the same.

Another object is to provide such construction for overhead ice tank units that they will provide adequate refrigeration for railway cars with smaller supplies of ice than those required by conventional ice bunkers.

Other objects and advantages will be apparent from the following detailed description, the appended claims, and the accompanying draw-

ings which latter illustrate a preferred embodiment of this invention.

Referring to the drawings,

Figure I is a top plan view of a railway refrigerator car and overhead ice tank units arranged therein in accordance with this invention.

Figure II is a longitudinal, vertical cross-sectional view taken on line II—II of Figure I and illustrates an embodiment of this invention.

Figure III is a perspective view of the overhead ice tank units, baffles and drip pan means shown in Figure II.

Figure IV is a transverse, vertical cross-sectional view taken on line IV—IV of Figure I, with parts broken away to facilitate illustration.

Figure V is a vertical, cross-sectional detail view taken on line V—V of Figure I, with parts broken away for purposes of illustration.

Figure VI is a rear elevational view of the ice tank unit at the end of the car in Figure II.

Figure VII is an elevational view of one side of the ice tank unit adjacent the center of the car in Figure II, the Figure VII view being taken on line VII—VII of Figure II.

Referring now in detail to the accompanying drawings, they illustrate a conventional railway refrigerator car provided with air refrigerating and circulating means embodying the present invention. The railway car has a lading space 1 and the usual car floor 2, ceiling 3, side walls 4, and end walls 5 (see Figures II and IV). The illustrated car is also of the type having centrally located side doors 6, and hatchways 7 extending through the car roof. These hatchways 7 may be lined with metal and are closed by means of hatchway covers 8. One of these hatchway covers 8 is omitted in Figure I to provide a view of the interior of the car from above the car roof. These hatchway covers 8 close the hatchways 7 when the car is to be used under refrigerating conditions and may be opened, as indicated by the dotted line position of the hatch cover 8 in Figure II, when ventilation of the car is desired. In the illustrated railway car, there are three hatchways 7 at each side of the car, although any desired number may be provided. The hatchways 7 are provided to permit loading of the car with ice and salt, but may be eliminated under certain circumstances if solid carbon dioxide is to be used as the refrigerant. The hatchways 7 are desirable if additional solid carbon dioxide will be required by the car in transit or if the car will require ventilation.

The railway car is provided with two series of ice bunkers or tank units 10. The two series of ice tank units 10 are arranged overhead and adjacent opposite car side walls 4. These two series of ice tank units 10 also preferably extend in opposite directions from adjacent the door section of the car to the respective ends of the car as illustrated in the drawings. In the preferred practice of this invention, a hatchway 7 is provided for and directly over each ice tank unit 10, so that each may be serviced individually.

Ice tank units

All the ice tank units 10 at the opposite sides of the car may be and are shown in the drawings of the same construction. A description of one ice tank unit 10 will, therefore, suffice for all. The ice tank units 10 preferably are relatively shallow to provide maximum head room below the units when supported adjacent the car ceiling 3. The depth of the individual ice tank

units 10 is, therefore, preferably less than their length or width. Each ice tank unit 10 has a lower portion comprising imperforate side, front and rear walls 11, 12 and 13 respectively and an imperforate bottom 14 for retaining a brine solution or concentrate. These lower tank unit portions, that is, the imperforate walls 11, 12 and 13 and the bottom 14, are preferably of corrugated metallic construction to strengthen the ice tank unit 10 and provide an increased area of outer surface for direct contact with air to be cooled. The wall and bottom members 11, 12, 13 and 14 of an ice tank unit 10, however, might be formed of flat sheet metal with fins or flanges on its outer side to increase its area of cooling surface. The tank bottom 14 also preferably slopes (see Figure IV) from the front wall 12 to the rear wall 13 to provide drainage for melting ice. The corrugations in the tank bottom 14 should also extend in the same direction as the slope thereof to facilitate drainage of the ice tank unit 10. A drainage collecting trough 15 is provided adjacent the rear wall 13 by suitably shaping that part of the tank bottom 14.

The ice tank unit 10 may be reinforced by partition means 16 extending between the opposite side walls 11 and similar partition means 17 extending between front and rear imperforate walls 12 and 13. These partition means 16 and 17 are preferably formed of apertured, corrugated sheet metal, but may be formed of other suitable material. These partition means 16 and 17 are also preferably welded to the tank unit side walls 11, 12, and 13 and to the tank unit bottom 14. The apertures in the partition means 16 and 17 provide for controlled circulation of the brine concentrate in the tank unit 10, and the corrugated shape of the partition means 16 and 17 provides substantial strength with a minimum of metal. The partition means 16 and 17 also avoid splashing of the brine concentrate and shifting of the ice within the tank unit 10.

Each ice tank unit 10 has its upper wall portions of foraminous construction. The upper tank portion is preferably formed of wire screening 18, as shown in the drawings, but may also be formed from perforated plates or by a louvered construction. Where wire screening 18 is used, it is desirable to provide a rigid reinforcing framework which may comprise side, front and metallic members 19, 20, 21, and 22. The metallic members 19, 20 and 22 may be formed of angle iron, and the member 21 may be in the form of a channel bar. Each part of the ice tank unit 10 which has now been described may be secured to the adjacent tank unit parts by welding, or in any other suitable manner, to provide a rigid and durable structure which requires no external reinforcement and will give efficient service over relatively long periods of time. It will be noted that the corner tie members or angle irons 22 are welded or otherwise rigidly secured at their lower ends to the lower imperforate ice tank portion and at their upper ends to the adjacent portions of the angle and/or channel irons (19, 20 or 21), and at their intermediate portions to the side wall screens 18.

A car may have as many of these ice tank units 10 as is desirable. The drawings show a preferred embodiment, in which a series of three ice tank units 10 are provided within each half of the car. However, a single ice tank unit of appropriate length may be substituted for each series shown in the drawings. The ice tank units 10 of each series are arranged with the horizon-

tal flanges of their side angle irons 19 in close or abutting relation to define the upper limit for air spaces or passages 23 (see Figures III and V) extending between adjacent sides of the ice tank units 10. A similar air passage 24 is provided between the car end wall 5 and the adjacent ice tank unit 10 (see Figure V). The ice tank units 10 at their upper edges are also spaced from the adjacent car side wall 4 (see Figures III and IV) by their channel irons 21 to provide a continuous air space or passage 25 along the adjacent car side wall 4.

Each ice tank unit 10 may be supported from the adjacent inner car side wall 4 by means of hinge connections such as shown in Figures III, IV and VII. Each of these hinge connections comprises a bracket 30 having a vertically extending portion bolted to the car side wall 4 and a horizontally extending arm portion 31 pivotally connected at its outer end to a strap 32 which may be welded or otherwise suitably secured to a tank bottom 14. The bracket 30 may be reinforced by a web or brace portion 33 extending between and secured to the vertical and horizontal parts of bracket 30. It will be noted that this bracket 30 not only serves to pivotally support its respective ice tank unit 10, but also serves to maintain the desired distance between the lower portion thereof and the adjacent car side wall 4 for forming the air passage 25. Each tank unit 10 may be pivotally supported by two or more of the brackets 30 arranged on the adjacent side wall 4 in spaced relation.

A preferred arrangement of ice tank units 10 is illustrated in the drawings, but other arrangements may be used without departing from the broader aspects of this invention.

Each ice tank unit 10 is also secured in the merchandise chamber so as to be maintained in the substantially horizontal position indicated by Figures II and IV for normal refrigerating service. The ice tank units are preferably secured to the merchandise chamber ceiling 3 or car roof with the horizontal flanges or portions of the tank unit angle bars 19 and 20 abutting on the chamber ceiling 3. The tank units may be releasably secured in this operative position by removable bolts 35 (see Figures II and IV) extending through the horizontal flanges of the angle bars 20 and into or through adjacent car roof supporting members. The width of a tank unit 10 is preferably about one-half the width of the car interior. The angle irons 20 will, therefore, be secured in place along substantially the longitudinal center of the car. If foraminous plates take the place of the screens 18, the former may be provided with flanges similar to the horizontal flanges or portions of the angle and channel irons 19, 20 and 21.

Combined air baffle and drip pan means

Each series of ice tank units 10 is also provided with means forming a continuous air baffle and drip pan for all the ice tank units 10 in the series. This means may comprise a sheet metal member 36 for each ice tank unit 10. Each sheet metal member 36 has a vertical baffle portion 37 constituting a section of said continuous air baffle. Another portion 38 of each sheet metal member 36 is disposed below the respective ice tank unit 10 to serve as its drip pan. This drip pan 38 preferably slopes downwardly toward its rearward portion which is suitably shaped to provide a drip-collecting trough 39 (see Figure IV). The combined baffle and drip pan members 36 are preferably spaced from their respective ice tank units

10 to provide communicating air passages or conduits 40 and 41 (see Figure IV). The air in circulating downwardly through air passage 40 and then through air passage 41 will be cooled and tend to reduce in volume. It is, therefore, preferred that the air passage 41 gradually becomes smaller in depth toward its outlet end adjacent the car side wall 4 to compensate for this change in the air and to maintain maximum contact of the air with the chilled tank bottom 14.

The combined drip pan and air baffle members 36 are preferably supported solely by the ice tank units 10. This support may comprise a plurality of suitably positioned brackets 45 welded or otherwise suitably secured to the outer surfaces of the ice tank units 10. The combined baffle and drip pan members 36 are detachably secured to these brackets 45 by means of bolts 46 and nuts 47. Installation and removal of the combined baffle and drip pan members 36 may be facilitated by welding the heads of the bolts 46 to the brackets 45 and having the nuts 47 threaded on their respective bolts 46 from the outer side of the combined baffle and drip pan members 36.

The adjacent edges 48 of adjoining sheet metal members 36 preferably meet intermediate the ice tank units 10, as shown by Figures III and V. To prevent the drip of the ice tank units 10 from passing between the adjacent drip pan edges 48, the latter may be assembled as shown in Figure V. The drip pan edges 48 are preferably curved and arranged to provide a raised rib, over which is positioned a correspondingly curved removable strip 49 to serve as a cover plate or seal for the drip pan joint. The sealing strip 49 and the curved drip pan edges 48 are secured in assembled relation and to adjacent brackets 45 by means of bolts 46, nuts 47 and washers 50, which latter are shaped to conform to the rib formed by the curved edges 48. A plurality of these brackets 45 may be so secured to the opposed sides of adjacent ice tank units 10 that alternate brackets 45 will be carried by one of the ice tank units 10 and the remaining brackets 45 by the other ice tank unit 10. This alternating arrangement of brackets 45 will serve not only to support the combined baffle and drip pan members 36, but also to maintain the ice tank units 10 in the desired spaced relation for providing the air passages 23. A joint such as has just been described for adjacent drip pans 38 may also be provided for adjacent air baffle members 37.

Although the combined drip pan and air baffle means for a series of ice tank units 10 has been illustrated in the drawings as formed of a plurality of sheet metal members 36, it will be apparent that a single continuous member extending the entire length of the respective series of ice tank units 10 might be used in their stead.

At each car end, the adjacent drip pan member 38 may have an upstanding flange 51 (see Figures III, V and VI). The car ends 5 may carry a plate member 52 having a lower offset portion 53 to provide with the car end wall a slot for receiving the adjacent drip pan flange 51. This construction for the drip pans 38 at the car ends deflects the drip and also prevents its splashing over the drip pan edge.

To avoid splashing of the drip on merchandise adjacent the doorway section of the car, the adjacent drip pans 38 may have upstanding flanges or baffles 54 as shown in Figures V and VII.

Means for draining ice tank units and drip pans

The drainage trough 15 of each ice tank unit

10 slopes toward an outlet opening 58 which may be located below partition means 17 and midway between the trough ends, as shown in Figure III. This outlet opening 58 has threaded connection 5 with a removable pipe fitting 59 leading into a drain pipe 60 which terminates below the railway car. In order to provide for controlled discharge of the brine concentrate or other liquid from each ice tank unit 10, a valve 61 of any 10 suitable form may be provided for each of the respective drain pipes 60. Each valve 61 is actuated by a link 62 connected at one end to an operating rod 63 which extends upwardly through the car roof. The end of each operating rod 63 15 above the car has a handle 64 (see Figure I) which is raised to the dotted line position of Figures IV and VI to open the respective valve 61 and is lowered to the full line position of those figures to close its valve 61. Each handle 20 64 is preferably positioned to overlie the surrounding top edge or frame of the respective hatchway 7, as shown in Figures I and IV, in order that its rod 63 must necessarily be in the lower position to close the respective valve 61 when the 25 corresponding hatchway 7 is closed by a hatch cover 8. The hatch covers 8 are always in position to close the hatchways 7 when the railway car is in transit and operating under refrigeration conditions. The valves 61 will, therefore, 30 be kept closed during car movements and prevent the brine concentrate from dropping on the right of way. The valves 61 cannot be opened when the hatch covers 8 are in the closed position, nor can the hatchway covers 8 be lowered 35 to their closed position when the handles 64 are in the open-valve position. When the hatch covers 8 are raised, the respective handles 64 are exposed for operation to open the corresponding valves 61 and drain the individual ice tank units 40 10. A suitable notch might be provided in each hatch cover 8 to conveniently receive the underlying handle 64 when the former is in position to close its hatchway 7. The ice tank unit channel bars 21 may also be notched or apertured 45 at 65 (see Figure III) to accommodate the rods 63 which extend therethrough.

As air circulates along and in contact with the imperforate walls 11, 12 and 13 and bottoms 14 of the ice tank units 10, it is refrigerated and loses at least some of its moisture content by condensation. This condensate or drip is collected by the drip pans 38 and drains into the troughs 39. Each trough 39 has an outlet connection 66 fitting into and detachable from a pipe 67 which communicates with the respective drain pipe 60 below its valve 61 for continuously discharging the condensate as rapidly as it collects on the respective drip pan 38. A detachable pipe fitting 68 may be provided in each drain pipe 60 to facilitate disconnection between the ice tank units 10 and their drainage connections as well as between the drip pans 38 and the pipes 67. It will also be noted here that the rear edges of the drip pans 38 are shaped to so accommodate the pipe fittings 59 that the drip pans may be removed or installed without disturbing the pipe fittings 59.

Side wall and floor racks

70 The air refrigerated by the ice tank units 10 and their contents will serve its purpose best if properly distributed throughout the car lading space. The car may, therefore, be provided with side wall and floor racks to assist in the distribution of the refrigerated air. The side wall

racks may comprise spaced uprights 70 and a foraminous partition in the form of spaced slats 71. This construction will provide vertical air passages or conduits 72 (see Figure III) between adjacent uprights 70 and also outlet openings 73 between adjacent slats 71. Cold air coming from the ice tank units 10 will flow downwardly through these conduits 72. Part of this air will find exit through the outlet openings 73 in the form of a plurality of horizontally directed streams; and the remainder will find exit from the conduits 72 at their lower ends.

The spacing of slats 71 may be uniform in accordance with conventional practice, but the preferred arrangement is to have the slats 71 adjacent the car floor 2 spaced further apart than the slats 71 adjacent the ice tank units 10. The spacing of the slats 71, for example, may be such that the area of outlet for the refrigerated air progressively increases from adjacent the ice tank units 10 to the car floor 2. By spacing the slats 71 in the manner indicated as preferred, the air will be so distributed within the lading space 1 as to provide a more uniform temperature throughout the car lading space. The preferred spacing will provide for the greater part of the refrigerated air being released adjacent the car floor, in order that there will be adequate cold air circulation over the entire width of the car. If the merchandise chamber is provided with a double deck, such as shown in Patents 2,077,649 and 2,077,650, dated April 20, 1937, or other multiple deck structure for supporting the lading, the side wall slats 71 may be so relatively spaced that larger spaces 73 are provided immediately below each deck to supply the space below each deck with sufficient freshly cooled air.

The uprights 70 may be of solid construction, as shown in the drawings, to prevent air circulation between the conduits 72 or may be of foraminated or perforated metal or other suitable material to provide a substantially continuous air space extending the full length of the side wall slats 71 and along the adjacent side wall 4.

The end wall slats 74 (see Fig. II) may be spaced similarly to the side wall slats 71 to present a uniform and more attractive appearance.

The main car floor 2 is provided with a false or foraminous floor rack structure in the form of spaced floor rack slats 75 extending longitudinally of the car. These floor slats 75 are supported by floor rack stringers 76 which extend transversely of the car and rest on the main car floor 2. The floor rack stringers 76 are spaced apart to provide air conduits 77 extending along the car floor 2 from car side wall 4 to opposite car side wall 4. These floor conduits 77 receive their supplies of refrigerated air from the side wall conduits 72, which lose only part of their refrigerated air through the slat spaces 73. If air circulation is desired below floor slats 75 for the full length of the car lading space 1, the floor rack stringers 76 may be of open work of foraminous construction. The floor slats 75 are relatively spaced to provide spaces 78 (see Figure IV) through which refrigerated air may flow from floor conduits 77 into the lading space 1.

Uniform spacing, according to conventional practice, may be provided for the floor slats 75. In a preferred construction, however, closer spacing is provided for the floor slats 75 which are positioned below the ice tank units 10 than for the floor rack slats 75 at the opposite side of the car. The spacing of the floor slats 75 may be

such that they present a progressively increasing area of outlet openings from the side of the car below the ice tank units 10 to the other side thereof. This variation in floor slat spacing will provide a greater flow of cold air into portions of the lading space 1 adjacent the car side walls 4 opposite the ice tank units 10 than into the lading space portions below the ice tank units 10. However, the chilled air flowing away from the side wall at the right in Figure IV and through the outlet spaces 73 will supplement the cooling effect of the more limited flow of cold air rising through the floor slat spaces 78 below the ice tank units 10. The refrigerated air will, therefore, be so distributed by the slat spaces 73 and 78 that a substantially uniform temperature will be rapidly secured and constantly maintained in the car lading space 1.

The drainage connections and pipes which are located within the car to carry off ice meltage and water of condensation, are preferably placed within conveniently located side wall conduits 72. This arrangement will leave the lading space 1 clear of obstructions between the side wall slats 71 (see Fig. IV) and those at the opposite side of the merchandise chamber. In order to provide for ready access to the valves 61 and the pipes 61, the upper side wall slats 71, for example, the uppermost two at the right in Fig. IV, may be releasably secured to the uprights 70, as by means of screws.

Air circulation

During use of the illustrated apparatus for refrigerating railway cars, the warm air within the lading space 1 will rise and flow over the air baffles 37. A part of this air will be drawn downwardly into the air passages 40 and along the air passages 41 for cooling by direct contact with the corrugated exterior surfaces of the adjacent parts of the ice tank units 10. The cold air in passage 41 passes over the rear edge of the drip pans 38 and descends into the side wall conduits 72.

Another part of the warm air flowing over the baffles 37 will circulate through the screening 18 at the front and sides of the ice tank units 10, the air spaces 23 providing for circulation between adjacent ice tank units 10. Air entering the ice tank units 10 is chilled by direct contact with the ice. Part of this air, cooled directly by the ice, flows through the screens 18 at the rear of the ice tank units 10 and into the air spaces 25 (see Figure IV), which communicate at their lower ends with the side wall conduits 72. Another part of the air cooled by direct contact with the ice flows through the side screens 18 of the ice tank units 10 and downwardly in the air spaces 23, 24 and 55 (see Figure V) to the air passages 41. All the air cooled by the ice tank units 10 will, therefore, be directed into the side wall conduits 72 which supply the refrigerated air into the lading space 1 by way of outlet spaces 73 and also by way of floor conduits 77 and their outlet spaces 78.

The ice tank units 10 combine the advantages of two methods for refrigerating air and produce results which are not accomplished by either method when used alone. The two methods referred to are cooling by direct contact with ice and cooling by direct contact with surfaces refrigerated by a brine concentrate. By combining the two types of air cooling, the ice tank units 10 cool the air to a lower temperature in a shorter period of time than would be obtainable by the

use of either method without the other, and also provide in the lading space 1 a temperature or atmosphere different from that which would be produced by the use of only one of said methods.

Another advantage provided by the combined type of ice tank unit 10 is that the air cooled by direct contact with the ice and salt mixture passes from within the ice tank unit 10 and flows in contact with the outer surfaces of the tank portion retaining the brine concentrate. The difference in temperature between the air cooled by direct contact with the ice and salt mixture and the air chilled by direct contact with the tank walls which retain the brine concentrate produces such modifying influence of one temperature on the other that the formation of a frost incrustation on the outer surfaces of the tank unit 10 is avoided. As a result, air will come into more intimate contact with the external surfaces of the tank units 10, and release a greater number of heat units than it would otherwise. The effect is to provide a volume of refrigerated air which is suitable for transportation of meat, dairy products, vegetables or fruit, without deterioration in either class of commodity.

Cleaning and inspection of ice tank units

The support and relative arrangement which are provided by this invention for the ice tank units 10 and the combined baffle and drip pan members 36 facilitate their individual inspection, cleaning and repairing. As explained in the foregoing description, the pipe connections 59 and the pipes 67 are readily detachable from the respective ice tank units 10 and drip pans 38. A removable pipe fitting 68 may be provided in each drain pipe 60, so that the pipes 67, the pipe connections 59 and the valves 61 may be lowered or removed to permit ready removal of the respective drip pans 38 and lowering of the ice tank units 10. The uppermost side wall slats 11, for example, the uppermost two at the right in Figure IV, are also removed to permit access to the valves 61, the pipes 67, and the pipe fittings 68.

Each combined baffle and drip pan member 36 is also readily detachable from its respective ice tank unit 10 by removing the corresponding nuts 47. It will be noted at this point that each ice tank unit 10 provides the support for its respective baffle and drip pan member 36, which, therefore, need not be, and preferably is not, connected to or supported directly by the car side walls 4 or car ceiling 3. The bolts 35 of the ice tank unit 10 to be inspected, repaired or cleaned are then removed. Such ice tank unit 10 may now be lowered on its side wall hinge connection to the dotted line position shown in Figure VII or to a substantially vertical position, whichever may be desired for servicing of the lowered ice tank unit 10. It will now be evident that the ice tank units 10 in a series may be lowered and inspected either individually or as a group. Reassembly of the ice tank units 10, the combined baffle and drip pan members 36, and the drainage connections may also be easily accomplished. It will be noted that the ice tank units 10 carry brackets 45 to which are welded the bolts 46. This construction greatly simplifies attachment of the combined baffle and drip pan members 36 to the respective ice tank units 10.

The accompanying drawings show a railway refrigerator car with a single merchandise chamber or lading space 1, but this invention obviously may be used in railway cars having more than

one merchandise chamber 1. In the latter case, all the merchandise chambers might be provided with similar arrangements of the air circulating, refrigerating and ventilating means disclosed in the accompanying drawings.

It will be understood that the foregoing is illustrative, and that this invention includes all embodiments and modifications coming within the scope of the appended claims.

10 We claim:

1. In a railway refrigerator car, the combination with a merchandise chamber having a ceiling, a floor and side walls, of an ice tank unit arranged adjacent the chamber ceiling and one of said side walls, a flange extending from the upper edge of said ice tank to space the same from said side wall, means mounted on said side wall and pivotally supporting the lower portion of said ice tank unit in spaced relation with respect to said side wall, means securing said ice tank unit to the chamber ceiling and cooperating with said pivotal means to maintain said ice tank unit in position for refrigerating service, said securing means being releasable to permit said ice tank unit to be swung downwardly on said pivotal support.

2. In a structure of the character described for a merchandise chamber to be refrigerated, the combination comprising an ice tank unit to contain a refrigerant, brackets carried by and extending from outer surfaces of said ice tank unit, means including a drip pan, means for detachably securing said drip pan means to said brackets and in spaced relation with respect to said ice tank unit, and detachable drainage means for said ice tank unit and drip pan.

3. In a structure of the character described for a merchandise chamber to be refrigerated, the combination comprising a refrigerant container, brackets carried by said container, some of said brackets extending outwardly from a side wall of said container and other brackets extending below the bottom thereof, means including a baffle member and a drip pan, and means detachably securing said baffle and drip pan means to said brackets with the baffle member arranged along and spaced from said side wall and with the drip pan arranged below and spaced from the bottom of said container.

4. In a structure of the character described for a merchandise chamber to be refrigerated, the combination of a plurality of relatively spaced ice container units arranged adjacent the chamber ceiling, means providing a continuous water-tight drip pan for all said container units and formed of a plurality of sections, one section for each container unit, said drip pan sections being arranged side by side with their adjacent edges meeting below the space intermediate the respective container units, brackets carried by and extending below said container units at the adjacent sides thereof, and means for releasably securing said drip pan sections to said brackets.

5. A drip pan structure for overhead refrigerating means in a refrigerator car, said drip pan comprising at least two sections placed side by side and having adjacent portions curved and combined to form a rib, a strip extending lengthwise of and overlying said rib to prevent drip from passing between the said sections, and means for maintaining said sections, rib and strip in assembled relation.

6. An overhead ice tank unit comprising side and bottom walls to provide a refrigerant container having its length and width of greater di-

mension than its depth, the upper portions of said side walls being of foraminous construction to surround an ice and salt mixture, the lower portions of said side walls and said bottom wall being of imperforate construction to retain an ice and brine mixture and presenting irregular outer surfaces of enlarged superficial area, means providing with said imperforate side wall portions a rigid reinforcement and framework for said foraminous side wall portions, and means extending across the interior of said container for reinforcing the side walls thereof.

7. The combination with a railway car refrigerator chamber, of a refrigerant tank suspended therein, said tank comprising a reinforced imperforate bottom wall to support the refrigerant and carry off the refrigerant fluid, and a combined baffle and drip pan of imperforate construction to collect condensation fluid, said combined baffle and drip pan being suspended from and detachably secured to said tank.

8. In a railway refrigerator car, the combination with a merchandise chamber having top, side and bottom walls, of an ice tank unit arranged adjacent the chamber top wall, means pivotally supporting said ice tank unit from one of said chamber walls, means cooperating with said supporting means to secure said ice tank unit in normal position for refrigerating service and releasable to permit pivotal movement of said ice tank unit, and air baffle means detachably secured to said ice tank unit.

9. In combination with a railway refrigerator car merchandise chamber, an overhead tank unit constructed to retain an ice and brine mixture, brackets rigidly secured to and extending from the outer wall surfaces of said tank unit, and means including a combined drip pan and air baffle for said tank unit, said means being suspended from and detachably supported solely by said brackets.

10. In combination with a merchandise chamber to be refrigerated, an overhead ice tank unit arranged adjacent the chamber ceiling, said ice tank unit having side and bottom walls to provide a refrigerant container, the upper portions of said side walls being of foraminous construction to surround an ice and salt mixture, the lower portions of said side walls and said bottom wall being of imperforate construction to retain an ice and brine mixture and being of irregular contour in cross-section to provide strength for the container and to present irregular outer surfaces of enlarged superficial area for contact with air to be cooled, means pivotally connecting said tank unit to a side wall of said chamber, means detachably connecting an upper wall portion of said tank unit to the chamber ceiling and cooperating with said pivotal connecting means to maintain said tank unit in position for refrigerating service with said tank unit bottom wall suspended from and supported by the side walls of the tank unit, and a combined drip pan and baffle extending below said ice tank unit and upwardly at least one side thereof to a level substantially above the level of the bottom wall of said tank unit, said drip pan and baffle and said tank unit being detachably connected and closely spaced to provide air circulating passages therebetween, whereby warm air within the chamber will rise, pass over said upwardly extending baffle, and circulate through said tank unit foraminous wall portions for cooling by direct contact with ice as well as along the irregular outer surfaces of said

tank unit imperforate portions for cooling by direct contact therewith.

11. In combination with a merchandise chamber to be refrigerated, an overhead ice tank unit comprising side and bottom walls to provide a refrigerant container, the upper portions of said side walls being of foraminous construction to surround an ice and salt mixture, the lower portions of said side walls and said bottom wall being of imperforate construction to retain an ice and brine mixture and being of irregular contour in cross-section to provide strength for the container and to present irregular outer surfaces of enlarged superficial area for contact with air to be cooled, and baffle and drip pan means spaced from and supported solely by said ice tank unit to provide therewith a passage for leading circulating air into contact with said outer surfaces of enlarged superficial area.

12. In combination with a merchandise chamber to be refrigerated and having side walls and a top wall or ceiling, an overhead ice tank unit comprising side and bottom walls to provide a refrigerant container, the upper portions of said side walls being of foraminous construction to surround an ice and salt mixture, the lower portions of said side walls and said bottom wall being formed of imperforate corrugated sheet metal to retain an ice and brine mixture and to provide strength for the container as well as to present irregular outer surfaces of enlarged superficial area for contact with air to be cooled, and means for detachably suspending said ice tank unit from the chamber ceiling and for pivotally connecting said tank unit to a chamber side wall, whereby the ice tank unit is supported for refrigerating service and the lading space below and at the side of said ice tank unit is unobstructed by tank unit support means and whereby the ice tank unit may be detached from said chamber ceiling and swung on the chamber side wall pivotal connection for inspection and cleaning.

13. In combination with a merchandise chamber to be refrigerated, an overhead ice tank unit comprising side and bottom walls to provide a refrigerant container, the upper portions of said side walls being of foraminous construction to surround an ice and salt mixture, the lower portions of said side walls and said bottom wall being of imperforate construction to retain an ice and brine mixture and being of irregular contour in cross-section to provide strength for the container and to present irregular outer surfaces of enlarged superficial area for contact with air to be cooled, baffle means spaced from said ice tank unit walls to provide therewith a passage for leading air refrigerated by the refrigerant and said outer surfaces of enlarged superficial areas to a side wall of said chamber, and at least one conduit to receive refrigerated air flowing from said passage and having side wall outlet openings through which the refrigerated air flows into said chamber, said conduit extending vertically at a side wall of said chamber and having its said openings of such size and position that openings at one level of said chamber present a greater area of outlet for said refrigerated air than openings at a different level of said chamber.

14. In a refrigerator car having a roof provided with a hatch opening, the combination with said roof of an ice container having a bottom section spaced below said roof, said bottom section including an imperforate bottom wall and

imperforate side and end walls and having baffles arranged to divide said section into a plurality of compartments accessible for loading through said hatch opening, each of said baffles having openings therein and said baffles being arranged to retard surging of the contents of the container.

15. A structure of the type set forth in claim 14 in which said container includes a foraminous wall section extending from each of the side and end walls of the bottom section to the roof of the car.

16. In a refrigerator car having a roof provided with a hatch opening, the combination with said roof of an ice container located within the lading space of said car and an air flue structure cooperating with said container to promote a movement of air in a circuit having a portion parallel to a side wall of the car; said container including an ice supporting section and a foraminous ice retaining section interposed between the first mentioned section and the roof of the car; the ice supporting section including side and end walls, each in alignment with one of the walls of the ice retaining section, an imperforate bottom and a surge preventing structure arranged to form in effect a plurality of baffles intersecting one another below said hatch opening and each connecting one wall of the ice supporting section to the opposite wall thereof; each baffle being provided with a series of openings spaced above said imperforate bottom and having its top edge flush with the top edges of the walls connected by such baffle; the air flue structure including a wall section parallel to and spaced from one of the side walls of the container, a second wall section extending from the first section in parallelism with and in spaced relation to said imperforate bottom and a third section extending from the second section in parallelism with and in spaced relation to said side walls of the car.

17. A structure of the type set forth in claim 14 wherein said container extends substantially to the roof of the car and wherein an upper portion thereof is foraminous.

18. In a refrigerator car having a roof provided with a hatch opening, the combination with said roof of an ice container located adjacent said roof and an air-flue structure cooperating with said container to promote a movement of air in a circuit having a portion parallel to the side wall of said car, said container having an imperforate lower portion and a perforated upper portion, and a surge retarding structure arranged to form in effect a plurality of baffles intersecting one another below said hatch opening and dividing said container into compartments, each of said baffles connecting one wall of the container with the opposite wall thereof, said structure providing openings between said compartments, said air-flue structure including a wall section parallel to and spaced from one of the side walls of the container, a second wall section extending from the first section in substantial parallelism and in spaced relation to said imperforate bottom, and a third section extending from the second section in parallelism with and in spaced relation to said side wall of the car.

19. In a railway refrigerator car merchandise chamber having a ceiling, a floor, end walls and side walls, said chamber being provided with vertically extending air conduits at each of the chamber side walls and transversely extending air conduits on the floor of the chamber, said side

wall and floor conduits communicating with the interior of the merchandise chamber and also with each other, the combination comprising two series of overhead ice tank units positioned adjacent the merchandise chamber ceiling and being located substantially at diametrically opposite positions in said chamber, each of said series extending along a side wall of said chamber for substantially half the length thereof and having a width corresponding substantially to one-half the width of said chamber, one series being located along one chamber side wall and the other series being located along the other chamber side wall, whereby said chamber is adapted for loading with merchandise below each ice tank unit series from the chamber floor to adjacent the ice tank units and for loading with merchandise from each tank unit series to the opposite chamber side wall for the full height of said chamber, each of said ice tank units having a foraminous upper wall portion for an ice and salt mixture and an imperforate lower portion for a brine concentrate, and means providing an air baffle and drip pan for each of said series of tank units, each of said means extending along the front wall portions of all the ice tank units in the respective series to provide said air baffle and beneath all the respective ice tank units to provide said drip pan, each of said means being spaced from the respective ice tank unit front wall portions and the respective ice tank unit bottom portions to provide with said ice tank units air circulating passages opening into adjacent merchandise chamber side wall air conduits; whereby warm air within the car will rise, pass over said baffles, and pass downwardly in adjacent side wall conduits for distribution into said merchandise chamber from said side wall conduits at opposite sides of the chamber and from said floor conduits.

20. In a refrigerator car, the combination with a merchandise chamber having a ceiling, a floor and a side wall, of a plurality of ice tank units arranged adjacent the chamber ceiling and said side wall, a plurality of means pivotally supporting said ice tank units to provide for independent pivotal movement of each of said ice tank units, said plurality of means being mounted on said side wall, and means for each of said tank units to secure said tank units independently to said chamber ceiling and cooperating with said pivotal supporting means to maintain said tank units in position for refrigerating service, the securing means for each tank unit being releasable to permit such tank unit to be swung downwardly on the corresponding pivotal supporting means independent of the position and movement of the other of said tank units.

21. An overhead ice tank unit for refrigerator cars and the like, said ice tank unit comprising a refrigerant container having its length and width of greater dimension than its depth, said container having foraminous upper side wall portions for an ice and salt mixture and imperforate lower side wall portions and bottom for retaining a brine concentrate, and foraminous partition members extending across the interior of said container and between opposite imperforate lower side wall portions thereof and being integrally secured to said opposite lower side wall portions and to said container bottom to reinforce said refrigerant container side walls and bottom and to reduce surging of said brine concentrate, said partition members having their upper edges at a

level not substantially higher than the upper edges of said imperforate lower side wall portions.

22. In a railway refrigerator car, the combination comprising a merchandise chamber, a hatchway extending through the car roof and chamber ceiling, a closure for said hatchway, an ice tank unit within said chamber and below said hatchway, said ice tank unit having at least an imperforate lower portion to retain a brine concentrate, a valve-controlled discharge for said tank unit, and operating means for said valve, said

5 operating means extending at all times through the car roof adjacent said hatchway and having a handle extending toward and between said closure and hatchway, said operating means and handle being adapted to be raised for valve opening operations when said closure is removed from said hatchway and preventing closing of said hatchway by said closure except as said handle is lowered to close said valve.
